Application January 30, 1959, Serial No. 54,402

Term of patent 14 years

(Cl. D48—31)

Figure 1 is a top plan view of a combined luminaire and slip fitter showing our new design;

Fig. 2 is a front elevation view thereof;

Fig. 3 is a view in rear elevation thereof;

Fig. 4 is a view in side elevation thereof;

Fig. 5 is a front perspective view thereof; and

Fig. 6 is a rear perspective view thereof.

The design disclosed is characterized by the combination of a luminaire having an inverted trough-like configuration and a slip fitter as best shown in Fig. 4.

We claim:

The ornamental design for a combined luminaire and slip fitter, as shown and described.
